IRONING HEAD DRIVE

Charles C. Scheele, Syracuse, N. Y., assignor to
Easy Washing Machine Corporation, Syracuse,
N. Y., a corporation of Delaware

Application February 24, 1948, Serial No. 10,501

2 Claims. (Cl. 74—48)

1

This invention relates to ironing machines, and more particularly to transmissions for driving the roll and ironing head of such machines.

In ironing machines of the type described, it is desirable to drive the roll at different selectable speeds for ironing different types of fabrics. It is desirable also to vary the speed of the roll without necessarily varying the rapid approach and retrograde motion of the ironing head into and out of engagement with the roll.

The present invention has as an object the provision of a plurality of speeds for the roll driving mechanisms, which may be selected at will.

A further object of the invention is the provision of simplified means to at will stop the roll rotation or cause the roll to rotate at one of two speeds.

A further object of the invention is to provide apparatus of the type described in which the roll speed may be varied without altering the speed of operation of the head toward and away from the roll.

A further object of the invention is to provide in apparatus of the type described, an improved clutch for controlling the movement of the head toward and away from the roll.

A still further object is to provide mechanism for the purpose described of relative simplicity and low manufacturing cost.

The above and other novel features of the invention will appear more fully hereinafter from the following detailed description when taken in conjunction with the accompanying drawings. It is expressly understood, however, that the drawings are employed for purposes of illustration only and are not designed as a definition of the limits of the invention, reference being had for this purpose to the appended claims.

In the drawings, wherein like reference characters indicate like parts:

Figure 1 is an end elevation of the transmission with the casing cut away;

Figure 2 is an enlarged longitudinal section taken substantially on the line 2—2 of Figure 1;

Figure 3 is a longitudinal section taken substantially on the line 3—3 of Figure 1;

Figure 4 is a transverse section detail taken substantially on the line 4—4 of Figure 3;

Figure 5 is a sectional detail taken substantially on the line 5—5 of Figure 4;

Figure 6 is a transverse section of the detail of Figure 4, taken substantially on the line 6—6;

Figure 7 is a transverse section taken substantially on the line 7—7 of Figure 2; and

Figure 8 is a sectional detail taken substantially on the line 8—8 of Figure 7.

Referring to the drawings, and more particularly to Figures 1, 2 and 3, there is shown a transmission for driving the usual ironing roll 10 in the

2

direction of the arrow A and for moving the ironing head or shoe 12 from engagement with the roll 10 as shown, to a position spaced therefrom and to the right of the position shown in Figure 1. The ironing roll is driven from the shaft 14 by means of a pinion 16 engaging an internal gear 18 concentric with and within the cylinder shell 20 of the roll 10. The movement of the head toward and away from the roll is effected through the rock shaft 22, head supporting arm 24, and the bifurcated lever 26 riding upon an eccentric 28. Both the roll, the shaft 14 and the rock shaft 22 are journaled in the back wall 30 of the gear casing 32, the construction being in many respects similar to that shown in Ringer Patent No. 2,083,505, issued June 8, 1937.

Power is applied to operate the roll and head from a vertically disposed shaft 34, suitably connected to a small electric motor or the like which operates at substantially constant speed, the shaft having a driving worm 36. An axially movable shaft 38, to which the eccentric 28 is splined, carries thereon a worm wheel 40 meshing with the worm 36 and is thereby adapted to continuously rotate at a substantially constant speed. A resilient spacing washer 43 arranged between the eccentric 28 and the worm wheel 40 provides an axial thrust upon these parts to cause them to position themselves against the front and back casing walls in the manner shown. The worm wheel 40 is freely rotatable upon the shaft 38 and is provided with a peripherally notched clutch disk 42 at one end for driving the ironing head eccentric 28, and dog teeth of a saw tooth shape 44 upon its opposite end for driving the roll 10.

The eccentric 28 has integrally formed therewith a radially extending ear 46 having a boss 48 upon which is pivoted a rocking actuating lever 50, the latter cooperating with a radially slid able clutch tooth 52 sliding in guides 54 and 56 and adapted to be moved to engagement with the notches 58 of the peripherally notched clutch disk 42. The lever 50 is biased by a spring 60 to move in a clockwise direction relative to the ear 46, and thereby to normally urge the sliding tooth 52 into a notch 58 of the clutch disk 42, it appearing that the lever 50 is positioned within a notched recess 62 in the face of the tooth 52. A manually operable stop 64, which may be swung into the path of the end surface 66 of the lever 50 or the opposite extremity 68 of the same lever, rocks the lever 50 into the position shown in Figure 7 to radially withdraw the tooth 52 from the disk 42 to thereby disconnect the eccentric from further rotation with the constantly rotating worm wheel 40. In order to cause the release movement of the tooth 52 from a notch 58 of the clutch disk 42, there is provided in a recess 70 in the outer end of the

tooth 52, a coil spring 72 and plunger 14, the latter bearing against the lever 50. Thus, upon disengagement of the tooth 52 by movement of the lever 50 resulting from engaging the stop 64, the spring 72 is first compressed until the frictional engagement of the tooth with the side walls of the notch 58 is broken, whereupon a snap release action is effected. It will thus be seen that by reason of the arms 66 and 68, rotation of the eccentric may be effected through 180° to either bring the ironing shoe 12 into engagement with the roll or to move it away from the roll to provide the usual clearance. The movement of the arm 26 is biased in a counter-clockwise direction by the spring 27 to prevent chattering.

In order to coordinate the starting and stopping of the roll 10 in its rotation, with the movement of the ironing head toward and away from the roll, the eccentric 28 is slidably keyed to the shaft 38 through the key 76, and the end 78 of such key forms a cam follower and rides against a face cam 80 formed on the end of the sleeve 82 fixed within the forward wall 84 of the housing. Thus, upon rotation from the position shown in Figures 1 and 2 of the eccentric through an angle of 180°, the shaft 38 is moved to the left against the urge of the biasing spring 86 contained within the hollow end of the shaft and bearing against the housing back 30. Freely rotatable upon the shaft 38 but constrained to move axially therewith by ring collars 88 and 90 is a step gear 92 having complementary saw tooth shaped dog teeth clutch elements 94 on the right hand face thereof adapted to cooperate with the teeth 44 on the face of the worm wheel 40. It will thus be seen that the clutch formed by the teeth 44 and 94 is engaged in the position shown in Figure 2 and released upon movement of the shaft 38 to the left in response to the action of the cam 80 and key follower 78.

The step gear 92 meshes with freely rotatable mating gears 96 and 98 mounted upon the shaft 14, and the teeth thereof are of sufficient breadth to permit the gliding movement without disengagement. Each of the mating gears are provided with saw tooth shape clutch teeth 100 and 102 on their adjacent faces, and are adapted to be engaged by similar teeth 104 and 106 upon the axially sliding clutch collar 108 splined to the collar 110, which is in turn keyed to the shaft 14. The clutch collar 108 is provided with an annular actuating groove 112 embraced by a sliding yoke 114 slidably positioned upon the stationary pin 116, which may act as a limit for the manual stop 64. In the forward housing wall 118 of the casing 32 (see Figure 4) there is positioned a manually operated stub shaft 120 having a crank 122 and a sliding block 124 riding in a transverse channel 126 in the sleeve portion 128 of the yoke 114.

The stub shaft 120 is enlarged in diameter as at 130 to form a collar engaging the side wall 118 and the portion so enlarged is notched in its cylindrical face as at 132, 134 and 136, to cooperate with a spring pressed detent 138 slidably received in a bore 140 in the side wall 118. The notches 132, 134 and 136 cooperate with the detent 138 to provide for movement of the stub shaft 120 to one of three positions, the central position of which places the yoke 114 in the position shown in Figure 3, where its clutch teeth 104 and 106 are out of engagement with the clutch teeth 102 and 100 of the gears 96 and 98. Movement of the stub shaft 120 to either end position

as determined by the notches 132 and 136, positions the clutch collar 108 to the right or to the left to engage the respective pairs of clutch teeth so as to complete a drive from the step gear 92 to one or the other of the gears 96 or 98 and thus to the roll 20. By the arrangement thus shown, the roll may be driven at either of two selected speeds at will or may be held in a stationary position should it be desirable to move the head into and out of engagement with the roll stationary for special pressing operations. It will also appear that the two speed arrangement is such as to provide a change of speed in the roll operation without slowing down the rapid movement of the ironing head into engagement with the roll or away therefrom. By the provision for an intermediate position of the control with both gear clutches disengaged, a separate clutch, or means to actuate the clutch formed by teeth 94 and 44 independent of the cam 80 and key follower 78 are rendered unnecessary to secure operation of the head with the roll stationary.

While a single embodiment of the invention has been illustrated and described, it is to be understood that the invention is not limited thereto. As various changes in construction, selection and arrangement of the parts may be made without departing from the spirit of the invention, as will be apparent to those skilled in the art, reference will be had to the appended claims for a definition of the limits of the invention.

What is claimed is:

1. In an ironing machine transmission, a casting, a shaft slidably mounted therein, a driven shaft mounted therein in parallel spaced relation to said slidably mounted shaft, a main drive member on said slidably mounted shaft having clutch teeth on one face, an ironing head operating eccentric on said shaft adjacent the other face of said drive member, means for axially moving said shaft in response to rotation of said eccentric, step gear means on said axially slidable shaft and movable axially therewith, and having face teeth adapted to engage or disengage said member face teeth upon axial movement of said shaft, gears meshing therewith on said driven shaft, a clutch device for connecting said eccentric to said drive member having a control lever, a manually movable abutment adapted to be positioned in and out of the path of said control lever, a casing supported stop extending parallel with said shafts to limit movement of said abutment, means for selectively coupling any one of said meshing gears to said driven shaft, and shifting means therefor, slidably mounted upon said casing supported stop.

2. An ironing machine transmission as set forth in claim 1, in which the shifting means has an eccentric receiving guideway and there is provided eccentric means cooperating with said guideway and journaled in the casing wall on an axis substantially transverse to the shafts.

CHARLES C. SCHEELE.
